M. F. BURNS

DENTAL FLASK

Filed March 24, 1922

INVENTOR
Martin F. Burns
BY E. W. Marshall
ATTORNEY

UNITED STATES PATENT OFFICE.

MARTIN F. BURNS, OF ASTORIA, NEW YORK.

DENTAL FLASK.

Application filed March 24, 1922. Serial No. 546,304.

To all whom it may concern:

Be it known that I, MARTIN F. BURNS, a citizen of the United States, and a resident of Astoria, county of Queens, and State of New York, have invented certain new and useful Improvements in Dental Flasks, of which the following is a specification.

This invention relates to dental apparatus and more particularly to dental flasks of the type used by dentists in casting plates, bridges, inlays and other restorations.

In casting a plate, bridge or other restoration a dentist first makes a pattern in wax of the article to be cast. The pattern is then invested in an initially plastic and quick hardening composition. When the investment is dry or has set the wax is melted out or otherwise dissipated, the cavity is filled with molten metal. The casting is then allowed to cool and is preferably cooled slowly to prevent warping or distortion. When warping or distortion takes place it is necessary to swage the casting to its proper shape.

It is very desirable that the rate of heating or cooling the investment and the parts contained thereby be regulated as different classes of work require different treatment.

This invention has for its object, therefore, to provide means in apparatus of the class described for regulating the heating or cooling of the investment and parts contained thereby.

Another object of the invention is to provide a construction by means of which the quantity of investment used will be conserved.

Further objects of the invention will appear from the following description taken in connection with the drawings which form a part of this application and in which,

Fig. 1 is an elevation, partly in section, showing a dental flask constructed in accordance with my invention and with the parts in assembled position.

Fig. 2 is a transverse sectional elevation taken substantially on line 2-2 of Fig. 1.

Fig. 3 is a bottom plan view of the construction shown in Fig. 1 with the investment holder and a receptacle in one position of relative adjustment and

Figs. 4 and 5 are views similar to Fig. 3 but showing the parts in their positions of adjustment.

The invention may be briefly described as including a receptacle and an investment

holder so relatively constructed and arranged that these parts may be relatively adjusted to regulate the rate of heating or cooling of the investment holder and parts contained thereby.

The receptacle 10 is preferably cylindrical in shape and has an imperforate wall, an open upper end 11 and a lower end partially closed by the bottom 12.

The bottom 12 is formed by an annular inwardly extending flange and this bottom has an oblong opening 13 formed therein. The side edges 14 of the opening are straight and the end edges 15 are curved on an arc having the axis of the cylindrical receptacle 70 shell as its center.

The investment holder comprises a pair of vertical, substantially parallel, spaced walls 16 connected at their upper and lower edges by strips or webs 17. At its upper 75 end the investment holder has formed thereon laterally extending flanges 18 conforming at their outer peripheral edges in shape to the inner peripheral wall of the receptacle 10. It will be seen from the showing in 80 Fig. 1 that air spaces 19 are formed at each side of the investment holder and between the walls 16 of the holder and the wall of the receptacle 10.

A cover 20 is provided for the upper end 85 of the receptacle and this cover has formed therein countersunk openings 21 through which the investment projects and by means of which the investment secures the cover to the receptacle. The cover 20 has also 90 formed thereon an upwardly extending cylindrical flange 22. As pointed out in the early part of the specification, after the wax pattern has been embedded in the investment, heat is applied to the apparatus and 95 this heat will cause the wax to dissipate thereby leaving a cavity in the investment. Gates or sprues are formed in the investment for conducting molten metal to the cavity left by the wax and one method of 100 filling the cavity is carried out by melting the metal by a blow torch whereupon it flows into the cavity and by applying air pressure to the apparatus to force the metal to entirely fill the mold or cavity.

For different classes of work the heating and cooling must be accomplished at different rates and in order to provide for this the receptacle and investment holder have 105 been designed in the particular manner.

above described. In Fig. 3 these parts are shown in the position in which air is excluded from circulating to or from the spaces 19 between the walls 16 of the investment holder and the receptacle. It should be borne in mind that the investment holder is filled between the walls 16 with the investment.

In Fig. 4 the holder and receptacle are adjusted to admit or permit the exit of a maximum quantity of air to and from the spaces 19. With the parts in this position in heating, the heat will be very quickly applied and in cooling the cooling effect will take place rapidly.

In Fig. 5 the parts are shown in another position of adjustment where the spaces 19 are partially open for the circulation of the air or the admission of a flame.

In order to obtain a still slower cooling effect I have shown in Fig. 1 means for sealing the receptacle thereby stopping the circulation of air and further retarding the rate of cooling. This means comprises a pair of caps 30 and 31 having lining material 32 therein and adapted to fit respectively over the bottom of the receptacle and over the top of the flange 22.

It is believed that the operation and method of using the various parts of the apparatus will be clear from the foregoing description without a further detailed statement thereof.

From the foregoing specification it will be evident that means has been provided for regulating through a wide range the rate of heating or cooling of the investment holder and the parts contained thereby. It will also be noted that the investment holder is so constructed that a minimum amount of investment is necessary.

Although one specific embodiment of the invention has been illustrated and described it will be understood that the invention is capable of modification and that changes in the construction and in the arrangement of the various cooperating parts may be made without departing from the spirit or scope of the invention as expressed in the following claims.

What I claim is.

1. In combination, a receptacle provided with a bottom having an angular opening therein and an investment holder adapted to be positioned in said receptacle comprising a pair of substantially vertical walls spaced apart a distance less than the maximum width of the opening in the bottom of the receptacle.

2. In combination, a receptacle provided with a bottom having an angular opening therein and an investment holder adapted to be positioned in said receptacle comprising a pair of substantially vertical, parallel walls spaced apart a distance less than the

maximum width of the opening in the bottom of the receptacle.

3. In combination, a receptacle provided with a bottom having an oblong opening therein and an investment holder adapted to be positioned in said receptacle comprising a pair of substantially vertical walls spaced apart a distance less than the maximum width of the opening in the bottom of the receptacle.

4. In combination, a receptacle, an investment holder adapted to be positioned therein with its walls spaced from the receptacle wall and means including the receptacle and holder for regulating the air circulation to the spaces at the sides of the holder.

5. In combination, a receptacle having an apertured bottom, an investment holder adapted to be positioned therein with its walls spaced from the receptacle wall and means including the receptacle and holder for regulating the air circulation to the spaces at the sides of the holder.

6. In combination, a receptacle having a bottom flange forming an oblong opening, an investment holder adapted to fit in the receptacle and having a pair of substantially vertical, spaced, parallel, walls, the opening in the receptacle bottom being longer than the distance between the spaced investment holder walls.

7. In combination, a receptacle having a bottom flange forming an oblong opening having straight sides, an investment holder adapted to fit in the receptacle and having a pair of substantially vertical, spaced, parallel, walls, the opening in the receptacle bottom being longer than the distance between the spaced investment holder walls.

8. In combination, a receptacle, an investment holder adapted to be positioned therein with its walls spaced from the receptacle wall and means including the receptacle and holder for controlling the communication between the spaces at the sides of the holder and the air surrounding the receptacle.

9. In combination, a receptacle having an apertured bottom, an investment holder adapted to be positioned therein with its walls spaced from the receptacle wall and means including the receptacle and holder for varying the openings between the spaces at the sides of the holder and the air surrounding the receptacle.

10. In combination, a receptacle provided with a bottom having an angular opening therein and an investment holder adapted to be positioned in said receptacle comprising a pair of walls spaced apart at the bottom a distance less than the maximum width of the opening in the bottom of the receptacle.

In witness whereof, I have hereunto set my hand this 22 day of March, 1922.

MARTIN F. BURNS.
